JACOB DODGSON, OF SEATTLE, WASHINGTON.

SELF-FIRING EXPLOSIVE BOMB.

1,161,461.

Specification of Letters Patent. Patented Nov. 23, 1915.

Application filed August 3, 1915. Serial No. 43,362.

To all whom it may concern:

Be it known that I, JACOB DODGSON, citizen of the United States, residing at Seattle, in the county of King and State of Washington, have invented a certain new and useful Improvement in Self-Firing Explosive Bombs, of which the following is a specification.

My invention relates to improvements in self-firing explosive bombs that are adapted for submarine work, and the object of my improvements is to provide a buoyant explosive bomb which shall embody clock-operated means for causing it to explode at a desired predetermined instant of time, and which shall be adapted to be carried by a submarine vessel to a point beneath a vessel to be destroyed and there be permitted to rise by its own buoyancy, while guided by means associated with said submarine vessel, secretly to engage with and automatically fasten itself to the bottom of the vessel to be destroyed, whereupon said guiding means may be disengaged, thus leaving the bomb fastened in its position to explode automatically upon the expiration of a predetermined period of time. I accomplish this object by devices illustrated in the accompanying drawings wherein—

Figure 1 shows my invention as embodied in a bomb and a submarine vessel with which it is associated, by a view in vertical mid-section, only a fragment of said submarine vessel being illustrated; and Fig. 2 is a view in side elevation of such bomb in engagement with the bottom of a vessel representing a war ship that is to be destroyed, together with a diagram representing a submerged submarine vessel provided with means by which said bomb was guided to and disposed upon the bottom of said war ship automatically to fasten itself thereto.

Referring to the drawings throughout which like reference numerals indicate like parts, a bowl-shaped iron receptacle 4 is provided with an integral hollow stud 5 which extends upwardly from the central portion of the inner surface of its bottom portion to project its upper end through a non-magnetic metal plate 6 which serves as a removable water tight cover for the receptacle 4, said plate 6 being bolted to an inwardly projecting integral flange 7 that is disposed within the upper part of the receptacle 4 there being provided a rubber gasket 8 that is disposed between the plate 6

and said flange 7 to make a water tight joint.

The top edge portion of the receptacle 4 that projects higher than the plate 6 is serrated to form teeth 9 therearound and disposed within the hollow stud 5 to be vertically movable therein is an iron plunger 10 whose top end terminates with a flange 11 whose top surface is provided with teeth 12 and within the lower portion of said hollow stud 5 is disposed a helical compression spring 13 upon which the plunger 10 rests and which serves to maintain said plunger 10 in a normal position whereby the toothed flange 11 will be in a higher plane than the serrated top edge of the receptacle 4.

Disposed to surround the hollow iron stud 5 is an electrical helix 14, the upper terminal of which is electrically connected to the plate 6 while its lower terminal is connected to one terminal of an electric battery 15, the other terminal of which battery 15 is electrically connected with an insulated contact spring 16 which is disposed in the path of the lower end of a metal plunger 17, said contact spring 16 being secured to the underside of a horizontal partition 18 which divides the interior of the receptacle 4 into two chambers 19 and 20.

The plunger 17 is slidably disposed within a socket 21 that is fixed to the underside of the plate 6 to extend downwardly therefrom, the lower end portion of said plunger 17 being disposed to project downwardly through the lower end of said socket 21 and through the partition 18 in a position to engage with the end of the contact spring 16 when such plunger 17 is depressed against the force of a helical compression spring 22 which is disposed to surround said plunger 17 within the socket 21 and which is adapted normally to maintain said plunger 17 at such elevation as will insure its disengagement with the end of the contact spring 16. The upper end portion of the plunger 17 extends through a packing box 23 and upwardly therefrom to a plane higher than the plane of the serrated top edge of the receptacle 4. Disposed to extend through the plunger 17 at a point adjacent to the top surface of the packing box 23 is a removable pin 24 that may serve normally to prevent the plunger 17 from being accidentally depressed to make contact with the contact spring 16.

The chamber 19 is filled with a suitable

explosive material, as gun powder, and embedded within such explosive material is a suitable ignition device 25 that is adapted to be operated by an electric spark which may be generated in the secondary winding 26 of an induction coil with which such ignition device 25 is connected by conductors 27 and 28, the primary winding 29 of such induction coil being connected one end to one terminal of the battery 15 by a conductor 30 while its other end is connected to an insulated contact point 31, which contact point 31 is disposed to adapt it to be engaged by a contact lever 32 that is pivotally attached to a clock 33, but electrically insulated therefrom, said contact lever 32 being connected by a conductor 34 with the other end of the battery 15 whereby when the lever 32 engages with the contact point 31, then current from the battery 15 will energize the primary coil 29 thus to induce a sparking current in the secondary coil 26 which will operate the ignition device 25 thus to ignite the explosive material within which it is embedded.

The lever 32 is operatively associated with the internal mechanism of the clock 33, in a well known manner not shown, whereby it may be actuated to make a contact with the contact point 31 at any desired predetermined instant of time in response to the operation of the clock 33, but normally, however, the mechanism of the clock 33 is at rest.

In order to control the operation of the mechanism of the clock 33 there is provided a lever 35 pivotally attached to said clock 33 which engages with a moving part of the mechanism of said clock 33, in a manner not shown, whereby a downward movement of said lever 35 will start the clock 33 to operate and such downward movement of said lever 35 may be effected by the operation of an electromagnet 36 which is adapted to attract an armature 37 attached to the outwardly projecting end of said lever 35. One terminal of the electromagnet 36 is attached to the wall of the receptacle 34, while its other terminal is connected by a conductor 38 with one terminal of the battery 15 whose other terminal is connected to the contact spring 16, whereby said magnet 36 will be energized to start the clock 33 to operate only when the plunger 17 is in engagement with the contact spring 16.

In order that one may gain access to the clock 33 for the purpose of setting its mechanism to cause the lever 32 to be actuated to make a contact with the contact spring 31 upon the expiration of a desired predetermined period of time after the plunger 17 has been depressed thereby to set the clock 33 in motion, there may be provided a hand-hole with a removable water tight cover, not shown, disposed in the wall of the

receptacle 4 at a point adjacent to the clock 33. Obviously, such access to the clock 33 can be had only before the receptacle 4 is placed in its position within the depression in the deck 39.

As shown in Fig. 1, the receptacle 4 is disposed within a depression in the deck 39 of a submarine vessel where it is secured to rest on the bottom of such depression by a releasable connector 40 which is fastened to the end of a cable 41, said connector 40 being releasably fastened to lugs 42 (which project downwardly from the bottom of the receptacle 4) by a hook 43 which is pivotally attached to said connector 40, as shown, and which is adapted by swinging movements to fasten and unfasten said connector 40 with respect to its engagement with the lugs 42. A cable 44 is attached to the hook 43 and such cable 44 together with the cable 41 extends downwardly through a tube 45 into a reel-box 46 that is secured to a part 47 of the submarine vessel. The tube 45 is provided with a flange on its upper end which is tightly joined to the bottom surface 90 of the wall of the depression in the deck 39 in a position concentric with the opening through which the lugs 42 project. The bottom end of the tube 45 is provided with a flange which is secured by a water tight 95 joint to the top wall of the reel-box 46, which reel-box 46 is itself water tight.

The top wall of the reel-box 46 is provided with an opening through which the cables 41 and 43 may be extended to wind 100 and unwind on reels 48 and 49, respectively, which are indicated by circular dotted lines in Fig. 1, said reels 48 and 49 being adapted to be rotated by cranks 50 and 51, respectively, the reel 49 being provided with a 105 ratchet 52 and a pawl 53 whereby when the hook 43 is in a position to fasten the connector 40 to the lugs 42, then the reel 49 may be turned forcibly to actuate the cable 41 to draw downwardly and hold the receptacle 4 on its seat within the depression in the deck 39, and then the pawl 53 by its engagement with the ratchet 52 will maintain said receptacle 4 firmly on its seat. The reel 48 may be free to revolve in either direction. 115

Associated with the deck 39 of the submarine vessel is a glass window, not shown, through which when the vessel is submerged one may look upwardly toward the surface 120 of the water and such vessel is also provided with a well known form of periscope, not shown, through which may be observed another vessel's movements.

The operation of the apparatus may be 125 described as follows: Through the periscope of the submarine vessel an enemy's vessel, as the vessel 55 in Fig. 2, is seen and thereupon the submarine vessel is submerged and directed in a course to pass under such ves- 130

sel 55 and when the submarine vessel reaches a point directly beneath such vessel 55 one may see the vessel 55 by looking up through the glass window in the deck 39, and therefore upon the pawl 53 on the reel-box 36 is disengaged from the teeth of the ratchet 52 to release the reel 49 whereupon the receptacle 4 by its own buoyancy will rise to engage with the bottom of the vessel 55 with the result that the plunger 12 will be depressed and the serrated edge of the top of the receptacle 4 will be pressed against the iron surface of the bottom of the vessel 55 and the plunger 17 will be depressed to make contact with the contact spring 16, (its safety pin 24 having been removed when the receptacle was placed in its position in the depression in the deck 39 of the submarine vessel) whereupon the current from the battery 15 will energize the helix 14 to magnetize the stud 5 and plunger 12 together with the annular wall of the receptacle 4, the teeth 12 making one magnetic pole while the teeth 9 make an opposite magnetic pole, thus causing the receptacle 4 to keep its place on the bottom of the vessel 55 as indicated in Fig. 2. The contact thus made between the plunger 17 and the contact spring 16 also causes the electromagnet 36 to attract the armature 37 thus to start the operation of the clock 33. The receptacle 4 having been thus attached to the vessel 55, the reel 48 is turned to pull the cable 44 to cause the hook 43 to move to release the connector 40, whereupon both reels 48 and 49 may be turned to haul downwardly the cables 41 and 44 against force of the buoyancy of a cork float 56 which is fixed to the upper end portion of the cable 41, which float 56 serves to prevent a too rapid falling of the cables 41 and 44 which otherwise might get tangled. The cables 41 and 44 having been reeled the submarine vessel may proceed on its course to other duty, and after the lapse of the predetermined period of time as fixed by adjustment of the clock 33 the lever 32 will be actuated to make contact with contact point 31 whereupon the ignition device 25 will ignite the powder in the chamber 19 and the resultant explosion may destroy the vessel 55 in an obvious manner. If the receptacle 4 should accidentally become detached from the vessel 55 before the explosion takes place the plunger 17 would rise and the clock 33 would stop by reason of the release of the armature 37. Obviously, in place of the electric helix 14, there may be employed equivalent means comprising steel permanent magnets secured to the receptacle 4 in a position to make contact with the bottom of an iron vessel, comparatively little magnetic force being required since the buoyancy of the receptacle 4 serves to force it against the bottom of such vessel, the magnetism serv-

ing only to prevent the device from slipping from one to another position.

Manifestly, a submarine vessel may have any convenient number of depressed seats in its deck thus to be prepared to place such 70 number of bombs in quick succession or simultaneously, and a supply of such bombs may be carried within the hull of a submarine vessel at all times.

Of course, changes may be made in the 75 forms, dimensions and arrangement of parts of my invention without departing from the spirit thereof.

What I claim is:

1. In a self-firing bomb of the class described, the combination with an iron receptacle closed on one of its sides by a removable plate of non-magnetic metal and having an iron stud disposed to extend from the central portion of that iron side wall 80 which is opposite said removable plate to and through the central portion of said removable plate, said receptacle being of a size and form to adapt it to float on a body of water with the weight of a desired load 90 contained therein, of a cable, one end of which is releasably fastened to the central portion of the outer side of the iron wall that is opposite said removable plate, whereby said receptacle may be releasably secured 95 in a submerged position in said body of water with said removable plate uppermost; a partition disposed to divide the interior space of said receptacle into two compartments; a mass of explosive material disposed in one of said compartments; an electric generator disposed in the other of said compartments; an electric circuit-breaker having one of its members electrically connected with the walls of said receptacle and 100 yieldingly disposed to extend upwardly from said other compartment to and through said removable plate to a plane higher than the top edges of said receptacle, while its other member is disposed within said other 110 compartment where it is electrically connected with one terminal of said electric generator; an electric helix disposed to surround said iron stud and having one of its terminals electrically connected with said removable plate while its other terminal is connected to the other terminal of said electric generator; a clock disposed in said other compartment and provided with an armature-lever in association with its mechanism whereby movements of said armature-lever may start and stop said clock; an electromagnet associated with said armature-lever, said electric generator and said circuit-breaker whereby said clock may be started 125 and stopped in response to the operation of said circuit-breaker; an induction coil disposed in said other compartment; an electric switch operatively associated with the mechanism of said clock with said electric gen- 130

erator and with the primary winding of said induction coil whereby said electric switch may be operated upon the expiration of a predetermined period of time after the 5 starting of said clock; an electrically operated ignition device embedded in said explosive material, and conducting wires disposed to connect said ignition device with the secondary winding of said induction 10 coil.

2. A self-firing bomb of the class described, which embodies a buoyant iron receptacle closed on one of its sides by a removable plate of non-magnetic metal and 15 having an iron stud disposed to extend from the central portion of that side wall which is opposite said removable plate to and through the central portion of said removable plate; electromagnetic means for magnetizing said iron stud and the iron walls 20 of said receptacle; a partition disposed

within said receptacle to divide its interior space into separate compartments; a mass of explosive material disposed in one of said compartments; an electric ignition device embedded in said explosive material; electric means for causing said ignition device to ignite said explosive material at the expiration of a predetermined period of time; and a cable releasably fastened to the 25 central portion of the other side of the iron wall that is opposite said removable plate, whereby said receptacle may be releasably secured in a submerged position in a body of water with said removable plate upper- 30 most.

In witness whereof I hereunto subscribe my name this 22nd day of July A. D., 1915.

JACOB DODGSON.
